(57) **CLAIM**

The ornamental design for a sterilization cassette, as shown and described.

DESCRIPTION

FIG. 1 is a top, front, right side, perspective view of a sterilization cassette showing our new design;

FIG. 2 is a right side view thereof, the left side view being a mirror image of the right side view;

FIG. 3 is a front view thereof;

FIG. 4 is a rear view thereof;

FIG. 5 is a top view thereof;

FIG. 6. is a bottom view thereof; and,

FIG. 7 is a top, front, right side, perspective view thereof in a disassembled state.

The broken lines depict portions of the sterilization cassette that form no part of the claimed design.
